UNITED STATES PATENT OFFICE

167,324

EMBROIDERED TRIMMING OR THE LIKE

John M. Sniderman, New York, N. Y.

Application September 28, 1951, Serial No. 16,773

Term of patent 3½ years

(Cl. D92—1)

To all whom it may concern:

Be it known that I, John M. Sniderman, a citizen of the United States, residing at city of New York, in the county of New York and State of New York, have invented a new, original, and ornamental Design for an Embroidered Trimming or the like, of which the following is a specification, reference being had to the accompanying drawing forming part thereof.

ornamental Design for an Embroidered Trimming, showing my new design.

Fig. 2 is an enlarged fragmentary view of the embroidered trimming shown in Fig. 1.

I claim:

The ornamental design for an embroidered trimming or the like, substantially as shown.

JOHN M. SNIDERMAN.
